UNITED STATES PATENT OFFICE.

FREDERICK EBEN HYATT, OF ST. DAVIDS, PENNSYLVANIA, ASSIGNOR TO THE KEY-STONE WATCH CASE COMPANY, OF PHILADELPHIA, PENNSYLVANIA, A CORPORATION OF PENNSYLVANIA.

DESIGN FOR A WATCHCASE.

50,911.

Specification for Design.

Patented June 12, 1917.

Application filed November 25, 1916. Serial No. 133,498. Term of patent 7 years.

To all whom it may concern:

Be it known that I, FREDERICK EBEN HYATT, a citizen of the United States, and a resident of St. Davids, in the county of Delaware and State of Pennsylvania, have invented a certain new, original, and ornamental Design for a Watchcase, of which the following is a specification.

In the accompanying drawing Figure 1 is a front view of a watch case showing my new design.

Fig. 2 is a view in side elevation thereof.

I claim:

The ornamental design for a watch case, as shown.

FREDERICK EBEN HYATT.

Witnesses:

H. P. LANDIS,
L. W. HAMPTON.
